FEEDING DEVICE

John D. Sasser, Springfield, Ohio, assignor to The Steel Products Engineering Company, Springfield, Ohio, a corporation of Ohio

Application September 3, 1943, Serial No. 501,112

17 Claims. (Cl. 89—38)

1

This invention relates to feeding devices for supplying a string of articles such as ammunition to a machine gun.

It is the principal object of the invention to provide a feeding device which is simple in construction, light in weight, and which in operation provides for supplying a string of articles to a place of use, and in which the weight of the string is supported with its upper level from which the articles are removed being maintained substantially uniform throughout the entire feeding operation.

It is a further object to provide an ammunition feeder which supports the greater part of the weight of a continuous string of ammunition and progressively advances the string toward the feeding position of the gun as it is utilized so that only a limited and substantially constant length of string is required to be supplied to the gun under the action of the gun mechanism, speeding up the gun action and making it more certain.

It is also an object to provide controls which operate promptly and positively to maintain the upper surface of the string of articles at a proper level and to sense the change of that level in anticipation of the requirement for further feeding action to assure positive and prompt maintenance of the articles at the desired level.

It is a further object to provide such a feeding device in which the reloading of the container with ammunition or other articles is facilitated and in which provision is made to prevent false or improper operation of the device, avoiding possibility of operation during loading or when not desired.

Other objects and advantages will be apparent from the following description, the accompanying drawing, and the appended claims.

In the drawing,

Fig. 1 is a view in side elevation of the rear face of a feeding device constructed in accordance with the present invention, certain parts being broken away to more clearly show the construction thereof;

Fig. 2 is a broken and elevational view of the device;

Fig. 3 is a side elevational view of the upper part of the device on a larger scale;

Fig. 4 is a broken side view showing the manner of feeding the ammunition and the control device therefor;

Fig. 5 is a top plan view of the device with parts broken away;

Fig. 6 is a side elevational view showing the way in which the upper tray is removable from the casing; and

2

Fig. 7 is a diagram of the circuit connections which are used.

Referring to the drawing which discloses a preferred embodiment of the invention, the casing for receiving the string of articles is shown generally at 10. For purposes of illustration the description will refer to the feeding of a string of ammunition, though the invention is not so limited. The casing is shown as rectangular in section and of sufficient depth to afford such capacity as desired. It is fabricated of suitable light weight materials and comprises side panels 11 and end panels 12, with a top flanged portion 13 adapted to be secured to a suitable part of the gun turret, thereby making the entire casing movable with the turret. Additional flanges 14 on the lower part of the casing provide for securing the same in proper position. Preferably the casing is mounted in a cradle supported from the turret so that it can be raised, lowered, and swung out away from the operative position to a clearance position for loading and servicing.

Within the casing there is mounted an ammunition supporting platform 15, this platform being mounted so that it can be raised and lowered. For this purpose the inner ends of walls 12 are provided with spaced vertically extending guides 16, and guide-block 17 is fastened to the platform for vertical travel therein. A flexible cable 18 passes underneath the platform and upwardly over sheaves 20 suitably journaled in brackets 21 conveniently formed as extensions of guides 16 on both sides of the casing. Sheaves 20 are mounted adjacent the upper end of the casing and the side walls 11 are apertured to permit the sheaves to extend therethrough, thus bringing the cable to the outer side of the casing where it passes downwardly. The cable may be clamped to the lower side of the platform by clamp 19 so that it may be adjusted to level the platform.

The ends 18a of the cable are secured to the opposite ends of a cross arm 22 which is provided with a central threaded part 23 which engages a feed screw 24. Such feed screw is suitably journaled at its upper end in a bearing 25 and in bearing 26 at its lower end, and also is supported and guided where it extends through bracket 39. The shaft extends below the bearing and on its lower end receives a gear 27 which meshes with pinion 28 on motor 29 having armature 29a and field 29b. A housing 30 encloses the gearing which thus constitutes a reduction gear mechanism for the relation of the shaft 24 from the drive motor 29. Motor 29 is of the reversible type and may be driven either in one direction or the other to cause the raising or the lowering of the

cross arm by reason of its threaded engagement with shaft 24. The construction is essentially self-locking and upon the deenergization of the motor, there is little if any tendency for it to be rotated in response to the load on the platform 15. Suitable electromagnetic brake means 32 connected in series with the motor armature are preferably provided within the motor and effective upon the motor shaft for assuring that the shaft will be held stationary when the motor is deenergized, such brake assuring also substantially the same degree of overrun each time the platform is stopped regardless of the load which it carries and its direction of movement.

In order to control the operation of the motor to provide for stopping its operation when the platform 15 approaches either end of its travel, limit switch means are provided for opening the circuit to the motor. Such means includes an upper limit switch 35 and lower limit switch 36, mounted adjacent each other on the frame 13. Push rods 37 and 38 extend downwardly from the respective switches and are guided at their lower parts in bracket 39 secured to the casing, each rod having its lower end projecting through the bracket as shown in Fig. 1. For actuating the rod 37 and hence the up limit switch 35, platform 15 is provided with a finger 40 which projects rearwardly through a vertically extending elongated slot 41 in panel 11. As the platform rises and reaches its upper limit, finger 40 engages and lifts rod 37 to open the motor circuit at switch 35, preventing further lifting of the platform. For actuating the rod 38 and the down limit switch 36, a finger 42 is carried on cross arm 22, being located in such position that as the platform is lowered and cross arm 22 rises to the desired limiting position, the finger will engage rod 38 to open the motor circuit at switch 36, preventing further lowering of the platform. It will thus be seen that these limit switches operate independently to make it impossible for the motor to actuate the platform in a given direction beyond a certain position. However, it will also be seen that whenever one limit switch is open, the other will be closed, and thus the motor will be able to reverse and thus to move the platform in the opposite direction.

It will be observed that the weight of the unused part of the string of ammunition on the platform varies substantially as the string is used and the platform is lifted. In order to facilitate the operation of the lifting mechanism under such circumstances and to tend to equalize the load imposed upon the drive motor, counterbalancing means are provided which is effective to counterbalance and compensate for the change in load on the platform. For this purpose a pair of spring assemblies are mounted in vertically extending tubes 45 which are fastened to the outside of the casing by suitable means including the brackets 39 on opposite sides of shaft 24. Each tube has a slot extending transversely therethrough through which the cross arm 22 extends. Each tube contains preferably a pair of springs which are arranged to telescope within each other in order to secure a greater range of travel. There is an upper spring 47 to the lower end of which is fixed a tubular member 48 which projects up into the spring, forming a chamber for receiving the lower spring 49 and rod 50 located inwardly thereof and shorter in length than tube 48. The upper end 48a of the tube 48 is at least partially closed to form an abutment for spring 49. The lower end of the rod 50 and spring 49 are adapted to

engage cross arm 22. Thus when the cross arm begins to move upwardly, spring 49 which is somewhat weaker than spring 47 is forced against the upper end of tubular member 48 and is progressively stressed until it is almost fully collapsed. At this time cross arm 22 will engage the lower end of spring 47 which has not been lifted to any material extent by the initial movement as described. Further upward travel of the cross arm 10 will however now compress spring 47 while keeping spring 49 under the tension originally applied, thus providing for developing a counterbalancing force which is greater when the cross arm 15 is raised and the platform 15 lowered, becoming progressively less as the platform rises and the weight of the ammunition remaining thereon becomes less. The motor operation is thus facilitated and the load made more uniform, making possible the use of a smaller sized motor 20 than would otherwise be required.

Mounted on the upper end of the casing and supported on flange 13 is a feed table or tray shown at 55. The tray does not entirely close the upper end of the casing but is spaced from one 25 end thereof to provide a passage through which the string of ammunition may be withdrawn. The tray comprises an upwardly inclined feed surface 56 below which there is positioned the guide roller 57 carried on cross pin 57a, the periphery of the roller being suitably shaped to correspond with the surface of the ammunition lengthwise thereof, and to provide for smooth and even support and feeding of the ammunition in 30 the arcuate path shown in Fig. 4, as the string is withdrawn from the casing and fed forwardly over the inclined surface 56. The tray is formed with laterally extending guides 58 at either side thereof which confine endwise movement of the ammunition as it travels across the tray. At its 35 forward end the tray is inclined downwardly as shown at 59 to provide for direct feed of the ammunition into the gun mechanism, the gun mechanism being utilized to draw the string of ammunition on to the feed table and into the gun 40 itself.

The feed table is removably supported on the casing 10 to provide for removal thereof for the purpose of replenishing the supply of ammunition on the platform. For this purpose the tray 50 seats in a recess in flange 13 and is formed with downwardly extending arms 60 which are apertured to receive pin 62 at their lower ends. Pin 62 is adapted to extend through suitable openings 55 provided in the upper edge of flange 13 to provide for locking the tray in the assembled position. Pin 57a similarly locks the tray in position, removal of the tray being possible only upon removal of both pin 57a and 62.

The ammunition is arranged in a continuous 40 string by means of clips indicated at 65 which connect each shell with the next in the series, permitting the swiveling of one shell freely with respect to adjacent shells. The ammunition is then piled on the platform in a series of layers, 45 extending back and forth across the platform. The upper end of the string is withdrawn from the remote or left-hand end of the casing and fed over guide roller 57 and the feed tray into position 50 to be engaged by the gun mechanism, as previously described.

It is desired to provide for control of the lifting of the platform automatically and without requiring the attention of the operator, and to cause the platform to be raised from time to 75 time as the ammunition is utilized, to maintain

the top of the pile or stack at substantially a uniform level. In this way the main body of the ammunition is supported without depending upon the lifting action of the gun mechanism, and a much larger quantity of ammunition can be included in the string without the necessity of reloading than would be the case if the gun mechanism were required to perform the entire lifting operation. Furthermore, particularly in the case of a machine gun carried by a rapidly moving body such as an aircraft, it is found that during certain types of maneuvers the additional loads imposed upon the gun mechanism through the action of centrifugal force or the like become very substantial, resulting in a tendency to so increase the drag of the string of ammunition where the gun is required to lift the entire string by itself that the operation of the gun is seriously interfered with, being substantially slowed down or even temporarily halted. With the present arrangement however the gun mechanism is required to perform only a relatively small part of the lifting operation, namely, to draw the upper end of the string comprising the upper one or two layers, and to lift only the limited distance from those layers to the feed tray and into the gun mechanism. Furthermore the load thus imposed does not vary substantially as the string is withdrawn, but remains substantially uniform throughout the entire firing of the gun from the time that the string is first fed to the gun until it is exhausted. As a result, the operation of the gun is made more definite and certain, and its firing under even the most severe conditions which may be encountered as a result of maneuvering, is assured and made rapid and uniform.

For the purpose of securing such control of the lifting of the platform, the tray 55 carries a feeler device for sensing the level of the upper layer of the ammunition. This feeler device comprises a shoe 70 which has a forwardly projecting toe portion 71 adapted to ride upon the upper level of the string of ammunition. This shoe is located adjacent the side of the casing opposite that through which the string is fed, the relationship being shown generally in Fig. 4. The shoe is carried by a shaft 72 which is guided for vertical movement in a sleeve 73 supported on the underside of tray 55 and is spring urged downwardly against the upper surface of the ammunition by spring 72a. The sleeve is formed with a cut-out section 74 and shaft 72 is also notched out, thereby forming upper and lower surfaces for engagement respectively with a nose piece 75 which extends outwardly into this notched-out part for the purpose of operating toggle switch 77 of which it forms a part. The switch is carried on a bracket 78 supported from the side of the tray and is of such character that it occupies either the up position shown in Fig. 4 in which it is open, or a down position in which it is closed. The switch is moved from one position to the other under the action of the nose piece 75 engaging the end of the switch arm to cause it to move with a snap action to one position or the other depending upon whether it is engaged by the upper or lower surface of the notch. A guard 80 is provided on the tray to enclose the switch and its operating mechanism in order to prevent possibility of the string of ammunition coming in contact therewith in the event of the aircraft turning over, for example. Guard 80 as well as the switch bracket 78 are offset as shown, at their portions to the left of and above the toe 71, making it possible for the ammunition to be lifted

upwardly into this offset space under certain circumstances.

The connections to the switch 77 are made so that the tray may be readily removed from the upper end of the casing without the necessity for disconnecting any of the wiring, and as readily replaced. For this purpose, the tray is provided with a pair of spring contacts 82 on one side, below the level of surface 56, with suitable wiring extending from the contacts to the switch 77. Stationary contacts 84 are provided on the upper end of the casing for engaging the respective contacts 82 when the tray is lowered to its operative position, thus providing a quickly detachable connection to the feeler switch. No changes need be made in the switch or its wiring as carried on the tray however since this remains as a permanently connected unit.

In order to facilitate access to the interior of the casing during loading for example, a front panel of the casing is provided with a removable section 90 which upon removal, provides access to the entire interior. This section 90 is flanged and is adapted to seat within inwardly projecting flanges 91 of the side panels 11. It is locked in place by a cross bar 92 the lower side of which overlies the section to retain it in place. Cross bar 92 is fastened in place to hold section 90 by means of a pair of wing nuts 93 which are loosened to allow the bar to lift up at its lower side sufficiently for the panel section 90 to clear the same, the bar 92 having elongated slots 94 (Fig. 3) to permit of such movement. The bar 92 may be retained in its raised position where its lower edge clears the panel 90 by tightening the wing nuts.

In order to prevent the feeler switch 77 from actuating the motor to cause the lifting of the platform during the loading of the casing and until such time as its automatic action is desired, a cut out switch 95 is provided which may be spring actuated to normally close the circuit to one of contacts 84 and arranged to open such circuit when depressed. The switch is mounted in a convenient position on the upper end of the casing and arranged to be actuated by a central tongue 96 on the cross bar 92 when the latter is held in its raised position. With the cross bar 92 in its lower or locking position with respect to panel section 90, tongue 96 is free of contact with switch 95 which is then in closed position and control of the operation is determined by the feeler switch 77. When however the bar is raised and the wing nuts tightened to hold it in raised position permitting the removal and replacement of the panel, the tongue 96 actuates switch 95 to open position thus disabling control of the motor by the feeler switch. The operator can thus carefully load the casing and make certain that the string of ammunition is properly arranged and is free to be withdrawn, without having the platform prematurely lift up to engage the top of the pile with the feeler switch. Upon the completion of the loading and the return of the panel section to close position, the dropping of cross bar 92 will cause withdrawal of the tongue from switch 95 which will thereupon close and restore control to the feeler switch under the main control of manual switch 100. The lifting of the platform is then under the control of the feeler switch which will cause the motor to lift the pile until the top of the pile raises the toe 71 to the full line position shown in Fig. 4 at which time further raising is terminated. It will be understood that the bar

92 may be lowered to effect closing of switch 95 even with panel 90 removed, if a raising of the platform is desired under those conditions.

A control switch box 100 is provided in a suitable location, preferably mounted at the upper end of the casing and comprises the manual control mechanism for reversing the operation of the motor when it is desired to lower the platform in the course of loading additional ammunition thereon. While the switch box 100 may contain a single composite switch, for purposes of simplicity it is shown as comprising two separate switches mechanically connected for simultaneous actuation, one being double pole and the other single pole, both being double throw. Thus a single pole switch 101 provides for selecting either the upper limit switch 35 or the lower limit switch 36. The double pole switch 102 reverses the motor circuit. Preferably the switch combination thus provided is normally biased to the position where the raising circuit of the motor is closed, and is adapted to be placed in the opposite or lowering position in response to manual operation. A suitable arrangement for this purpose is to spring bias the two switches into the raising position. The switch assembly may if desired be arranged to also remain in the lowering position.

Referring to the circuit diagram it will be observed that when the switch 100 occupies the lowering position, the circuit is from L+, switch 101, lower limit switch 36, switch 102, the armature 29a of the motor, switch 102, the field 29b of the motor, the magnetic brake 32 to the grounded negative. The lowering of the platform is thus under the control of the manual switch 100 until the lower limit of the platform is reached when it stops.

When the manual switch is in the raising position, the circuit is from L+, switch 101, top limit switch 35, one side of disconnect plug 84, socket 82, feeler switch 77, back through the disconnect plug and socket, interlock switch 95, switch 102, through the motor armature 29a in the opposite direction, the motor field 29b and the magnetic brake 32 to the negative ground, to give reverse operation. Operation is then under the joint control of manual switch 100, feeler switch 77 and the interlock switch 95 until the upper limit is reached when the motor stops.

In operation, with the platform loaded the upper level of the string of ammunition is as shown in Fig. 4, and such as to raise the feeler shoe 70 to its upper position, opening switch 77 and terminating further lifting movement of the platform. Under the operation of the gun, the string of ammunition is drawn upwardly thereby, resulting first in the withdrawal of the topmost layer of ammunition and allowing the feeler shoe 70 to drop to the level indicated by the second layer of ammunition in Fig. 4. However this movement is insufficient to cause the tripping of switch 77, and the level of the platform remains the same until the string has been drawn far enough to remove the first several shells of the second layer from beneath the toe 71 of the feeler device. At this time the feeler shoe drops into the dotted line position of Fig. 4 at which time it rests upon the third layer of ammunition. As it drops into this lower position, switch 77 is tripped and thus completes the circuit for the raising operation of the motor, the motor commencing to operate and lifting the platform with the ammunition thereon. Such lifting continues until the ammunition arrives at the upper

level where the shoe occupies its full line position, at which point switch 77 is opened and further lifting ceases. Even should the operation of the gun have ended immediately following the closing of this circuit, it will be clear that the top layer of ammunition occupies the recess beneath bracket 88 and does not contact or interfere with the switch mechanism.

Such lifting operation continues intermittently as the ammunition is used and under control of feeler switch 78 until the platform reaches its uppermost position where it engages upper limit switch 35, tripping the same to open position and deenergizing the motor.

In order to return the platform to its lower position, manual switch 100 is thrown to its reverse position, thereby disconnecting the feed switch 77 and directly connecting the motor in the reverse operating direction. Operation continues in this direction as long as the switch is held in reverse position, the platform moving downwardly as far as desired, and being stopped only when it reaches the lower limit of its travel by the opening of lower limit switch 36 or by release of the switch assembly 100. It will be noted that the lowering circuit does not include any of the mechanism carried by the feed tray and hence it is possible to operate the platform to lower the same while the tray is removed from the top of the casing, the operation in this respect being different from that for the raising operation.

The invention thus provides an ammunition feeding device for supplying a string of ammunition to a gun while maintaining the same at a substantially uniform level, entirely automatic and without the necessity of the operator operating the control. The gun action is thus facilitated and made more certain, and the entire arrangement is protected and assurance provided against accidental operation which might result in damage or injury to the operator.

The entire structure throughout is arranged so that the elements can be assembled to provide for right or left hand feeding, all structures being reversible so that two assemblies can thus be made. Such flexibility of arrangement is particularly desirable where it is desired to establish repair stations for aircraft gun turrets for example, the interchangeability of the ammunition feeder parts of this invention greatly facilitating and simplifying the number of parts required.

The invention has been described with reference to the feeding of ammunition to an automatic gun, by way of specific example, but is also applicable for the regulated supply and feeding of other articles where similar or analogous conditions are encountered.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A feeding device for an automatic gun utilizing a string of ammunition comprising a casing adapted to be mounted in fixed relation with respect to the gun and to receive the string of ammunition in a series of layers, said casing having a delivery passage for said string of ammunition through the top and adjacent one side thereof, a platform for supporting said layers of ammu-

tion, power actuated means for lifting said platform, and control means responsive to the level of the top layer and located in spaced relation with said one side of said casing and out of the path of travel of said string of ammunition for rendering said mechanism successively operative and inoperative as the ammunition is withdrawn from said casing through said passage to maintain the top layer of said ammunition within predetermined limits of level.

2. A feeding device for an automatic gun utilizing a continuous string of ammunition comprising a casing adapted to be mounted in fixed relation with respect to the gun and to receive the string of ammunition in a series of layers, said casing having a delivery passage for said string of ammunition through the top and adjacent one side thereof, a platform for supporting said layers of ammunition, power actuated mechanism for lifting said platform, and control means for rendering said mechanism operable intermittently as the ammunition is withdrawn from said casing, said control means including a feeler device located at the opposite side of said casing out of the path of travel of said string of ammunition and responsive to the level of the upper layer of ammunition in said casing to maintain said layer within predetermined limits of level.

3. A feeding device of the character described for feeding a continuous string of articles comprising a casing adapted to receive the string of articles in a series of layers, a platform within said casing for supporting said layers of articles, a feed table supported at the top of said casing over which said string of articles is fed upon withdrawal from said casing, a feeler device carried by said feed table and adapted to extend into said casing adjacent the upper end thereof for sensing the level of the top layer of said articles, and power actuated means operated under control of said feeler device for maintaining said top layer of articles at a predetermined level adjacent said feed table.

4. A feeding device of the character described for feeding a string of articles comprising a casing adapted to receive the string of articles in a series of layers, a platform within said casing for supporting said layers of articles, a feed table removably supported at the top of said casing over which said string of articles is fed upon withdrawal from the casing, a feeler device carried by said feed table and extending into the upper end of said casing for sensing the level of the top layer of said articles, power actuated means operated under control of said feeler device for lifting said platform to maintain said top layer of articles at a predetermined level, and means for disabling control of said power actuated means by said feeler device upon removal of said feed table from said casing.

5. A feeding device of the character described for supplying a string of articles comprising a casing to receive the string of articles in a series of layers, a platform within said casing for supporting said layers of articles, a feeler device extending into the upper end of said casing for sensing the level of the top layer of said articles, power actuated means operated under control of said feeler device for lifting said platform to maintain said top layer of articles at a predetermined level, and means for disabling control of said power actuated means by said feeler device during the loading of articles into said casing upon removal of said feed table from said casing.

6. A feeding device of the character described

for feeding a string of articles comprising a casing adapted to receive the string of articles in a series of layers, a removable cover member on said casing providing access to the interior of said casing, a platform within said casing for supporting said layers of articles, a feeler device extending into the upper end of said casing for sensing the level of the top layer of said articles, power actuated means operated under control of said feeler device for lifting said platform to maintain said top layer of articles at a predetermined level, and means for disabling control of said power actuated means by said feeler device upon removal of said cover member from said casing.

7. A feeding device of the character described for feeding a string of articles comprising a casing adapted to receive the string of articles in a series of layers, a removable cover member on said casing providing access to the interior of said casing, a platform within said casing for supporting said layers of articles, a feeler device extending into the upper end of said casing for sensing the level of the top layer of said articles, power actuated means operated under control of said feeler device for lifting said platform to maintain said top layer of articles at a predetermined level, means for disabling control of said power actuated means by said feeler device upon removal of said cover member from said casing, and manually actuated means operable when said cover member is removed for restoring control of the lifting of said platform to said feeler device.

8. A feeding device of the character described for feeding a string of articles comprising a casing adapted to receive the string of articles in a series of layers, a platform within said casing for supporting said layers of articles, a cross arm movable upon said casing, a flexible cable attached to said platform and to said cross arm for causing the raising and lowering of said platform in response to the opposite movement of said cross arm, a motor mounted on said casing, driving connections between said motor and said cross arm to cause operation of said cross arm and resulting travel of said platform, limit switches adapted to be positioned on said casing in side by side relation to each other, and means carried by said cross arm and said platform respectively for actuating said limit switches selectively upon the movement of said platform to the upper and lower limits of its travel.

9. A feeding device of the character described for feeding a string of articles comprising a casing adapted to receive the string of articles in a series of layers, a platform for supporting said layers of articles, motor means for raising and lowering said platform, means responsive to the level of the articles in said casing for controlling said motor means to maintain a constant level of the upper surface thereof, and additional means for counterbalancing the weight of the articles on said platform with a force varying progressively with the quantity of articles on said platform.

10. A feeding device of the character described for feeding a string of articles comprising a casing adapted to receive the string of articles in a series of layers, a platform for supporting said layers of articles, motor means for raising and lowering said platform, means responsive to the level of the articles in said casing for controlling said motor means to maintain a constant level of the upper surface thereof, and means separate from said motor means for developing a variable counterbalancing action on said platform de-

creasing in amount upon reduction of the weight of articles remaining on said platform.

11. A feeding device for an automatic gun utilizing a string of ammunition comprising a casing adapted to be mounted in fixed relation with respect to the gun and to receive the string of ammunition in a series of layers, a platform within said casing for supporting said layers of ammunition, power actuated means for raising and lowering said platform, control means for said power actuated means responsive to the upper level of said articles in said casing to maintain a substantially uniform level thereof, and resilient means for counterbalancing the weight of said ammunition on said platform with a force varying directly with the quantity of ammunition on said platform.

12. A feeding device for an automatic gun utilizing a string of ammunition comprising a casing adapted to be mounted in fixed relation with respect to the gun and to receive the string of ammunition in a series of layers, a platform within said casing for supporting said layers of ammunition, a feed table supported at the top of said casing over which said string of ammunition is fed to the gun, a feeler device carried by said feed table and projecting into said casing for sensing the level of the top layer of said ammunition, flexible cables on said casing for supporting and lifting said platform, a motor supported on said casing and connected to said cables to effect raising and lowering of said platform, and means for controlling the operation of said motor in response to the position of said feeler device to maintain said top layer at a predetermined level.

13. A feeding device for an automatic gun utilizing a string of ammunition comprising a casing adapted to be mounted in fixed relation with respect to the gun and to receive the string of ammunition in a series of layers, a platform within said casing for supporting said layers of ammunition, a feed table supported at the top of said casing over which said string of ammunition is fed to the gun, a feeler device carried by said feed table and projecting into said casing for sensing the level of the top layer of said ammunition, flexible cables on said casing for supporting and lifting said platform, a motor supported by said casing and connected with said cables to effect raising and lowering of said platform, means for controlling the operation of said motor in response to the position of said feeler device, and means for terminating further operation of said motor when said platform reaches upper and lower limits of its travel.

14. A feeding device for an automatic gun utilizing a string of ammunition comprising a casing adapted to be mounted in fixed relation with respect to the gun and to receive the string of ammunition in a series of layers, a platform within said casing for supporting said layers of ammunition, a feed table supported at the top of said casing over which said string of ammunition is fed to the gun, a motor operatively connected with said platform for raising and lowering the same, a feeler device for sensing the level of the top layer of said ammunition means for controlling said motor in response to said feeler device to maintain the top layer of said ammunition at a predetermined level, and a manual reversing switch normally biased to position to control said motor to effect the raising of said platform and adapted upon manual operation to

reverse the operation of said motor to effect the lowering of said platform.

15. A feeding device for an automatic gun utilizing a string of ammunition comprising a casing adapted to be mounted in fixed relation with respect to the gun and to receive the string of ammunition in a series of layers, a platform within said casing for supporting said layers of ammunition, a feed table supported at the top of said casing over which the string of ammunition is fed to the gun from one side of said casing, a feeler device carried by said feed table and projecting into the casing adjacent the other side thereof for sensing the level of the top layer of said string as said top layer is first removed from beneath said feeler device, and power actuated means operated under control of said feeler device for maintaining said top layer at a predetermined level.

20 16. A feeding device of the character described for feeding a string of articles comprising a casing adapted to receive the string of articles in layers, a platform within said casing for supporting said layers of articles, a motor operatively connected with said platform for raising and lowering the same, a feeler device for sensing the level of the top layer of said articles and controlling the operation of said motor in response thereto to maintain a predetermined level thereof, and a manual reversing switch normally biased to position to effect the raising of said platform and adapted upon manual operation to reverse the operation of said motor to effect the lowering of said platform.

30 17. A feeding device of the character described for feeding a string of articles comprising a casing adapted to receive the articles in a series of layers, a platform within said casing for supporting said layers of articles, a feed table supported on said casing over which the string of articles is fed from the top and adjacent one side of the casing, a feeler device projecting into the casing adjacent the other side thereof and out of the path of movement of the string of articles for sensing the level of the top layer of said string as said top layer is first withdrawn from beneath said feeler device, and power actuated means operated under control of said feeler device for maintaining said top layer at a predetermined level.

JOHN D. SASSER.
